UNITED STATES PATENT OFFICE.

JOHN W. DENMEAD, OF AKRON, OHIO.

BEAD-ROLLING MACHINE FOR PLASTIC ARTICLES.

1,091,123.

Specification of Letters Patent. Patented Mar. 24, 1914.

Application filed December 9, 1912. Serial No. 735,813.

To all whom it may concern:

Be it known that I, JOHN W. DENMEAD, a citizen of the United States, residing at Akron, in the county of Summit and State 5 of Ohio, have invented new and useful Improvements in Bead-Rolling Machines for Plastic Articles, of which the following is a specification.

This invention relates to machines for 10 manufacturing finger-cots, nursing-nipples, ice-bags, and the like, and has especial relation to means for forming the beads around the open ends of the articles.

Briefly, the majority of the articles before mentioned are manufactured by the dipping process on a form and thus are made with an open end. The formation of the open end of the article frequently is imperfect and rough and until reinforced by 20 a bead is a source of weakness, and hence, this invention contemplates means for trimming, if necessary, the neck or open end of the article and subsequently rolling up the same for forming a bead for strengthening 25 the article and improving its general finished appearance.

With the foregoing and other objects in view, the invention consists in the novel construction, combination and arrangement of 30 parts constituting the invention to be hereinafter specifically described and illustrated in the accompanying drawings which form a part hereof wherein is shown the preferred embodiment of the invention, but it is to be 35 understood that changes, variations and modifications can be resorted to which come within the scope of the claims hereunto appended.

In the drawings in which similar reference numerals indicate like parts in the different figures, Figure 1, is an end elevation of the device; Fig. 2, is a side elevation; Fig. 3, is a plan; Figs. 4, 5 and 6, are side elevations of details of the mechanism employed; and, Fig. 7, is a transverse sectional view of the device shown in Fig. 5 on line X thereof.

Referring to the drawings in detail, the device embodies a supporting frame consisting of end members 1 and 2 suitably spaced apart and secured on a suitably supporting medium such as a floor.

At the upper end of the member 2 are a pair of longitudinally-apertured bosses or lugs

3 constituting supports for mechanism to be 55 later described. At the upper ends of the arms of the member 1 are a similar pair of centrally-apertured lugs 4. Mounted in the apertured lugs 3 and 4 and secured against rotation are a pair of parallel rods 5 and 6, constituting ways for a slideable carriage, to be later described. Integral with and extending upwardly from the lugs 4 are housings 7 supporting bearings 8 and 9 in which is mounted a rotatable shaft 10, bearing a 65 cone-pulley 11 over one member of which runs a belt 12 for rotating the shaft 10. Either formed integrally with the inner end of the shaft 10 or secured thereto is a chuck or hub 13 in which is a conically-formed recess 14 (see Fig. 4). Adapted to be frictionally mounted in the recess 14 is a spindle 15 having a frusto-conically-formed end 16. The larger end of the conical portion 16 is provided with an integral hub or collar 17. 70 Extending from the collar 17 is an integral shaft 18. Secured on or formed integral with the shaft 18 is a lug 19 to which is secured a spring 20 the free end of which is provided with a detent 21 for constituting a 75 lock to be later described.

Adapted to be slidably mounted on the shaft 18 is a bushing 22 constituting a form-holding chuck and provided at its outer end with a face-plate 23 provided with apertures 24 to which is secured by hold-fast devices, or otherwise, a form 26 on which is mounted a nursing-nipple 27 constituting the article used to illustrate the application of this invention. The inner end of the 90 bushing 22 is conically-formed at 28 and the bushing is provided with one or more apertures 29. In order to secure the bushing 22 on the shaft 18 temporarily to compel its revolution in unison with the rotation of 95 the shaft, the bushing is slid longitudinally on the shaft 18 and the conical portion 28 forces the spring 20 and detent 21 outwardly and is rotated sufficiently to bring the detent 21 into registration with the aperture 29 causing the detent 21 to engage therein.

It will be noted that one face of the detent is approximately radial with the shaft 18, whereas the opposite face is inclined and as 105 the direction of revolution is such as to cause the radial end of the detent 21 to engage the side wall of the opening 29, the bushing 22

will be rotated in unison therewith, and if it is desired to remove the bushing and the form-bearing member, the bushing 22 is given a partial rotation forwardly, that is to say in the direction of rotation of the shaft 18 causing the inclined face of the detent 21 to engage the side wall of the opening 28 which raises the detent 21 out of the opening 29, thereby permitting it to be drawn longitudinally from the shaft 18, thus permitting another bushing with a form-bearing member to be substituted therefor.

The rotation of the shaft 18 and the form-bearing member is relatively slow, that is to say, approximately probably one hundred revolutions a minute and the placing of the form-bearing bushing thereon is easily accomplished by hand and when it is desired to remove the form-bearing member a slight forward rotation of the bushing by hand during the rotation of the shaft 10 is easily accomplished, the movement being sufficient to lift the detent 21 to permit the withdrawal of the bushing 22.

25 Mounted on the rods 5 and 6 as ways, is a carriage carrying the tools or equipment by which the various operations of trimming the article 27 and rolling up the bead thereon are accomplished, and this carriage embodies a pair of longitudinally-extending members 29 and 30 arranged in parallelism and each centrally apertured to be slidable on the bars 5 and 6. The members 29 and 30 are connected by cross-bars 31. Preferably formed integral with the member 29 is a bracket 32 on which is mounted a motor 33 provided with an armature shaft 34 usually revolving in the neighborhood of fifteen to eighteen hundred revolutions per minute.

40 Mounted on the armature shaft is an eccentric 35 to the strap of which is pivotally mounted an ear 36 at the end of a longitudinally-shiftable shaft 37 mounted in a bearing 38 on the upper end of a bracket 39 extending upwardly from the member 29. It will be apparent that as the motor revolves the shaft 37 will be alternately shifted or vibrated back and forth in its bearing 38. Secured on the shaft 37 between a pair of 45 fixed collars 40 is the pivotal end of a lever 41 which is bent at right angles at 42 and provided at its outer end with a handle 43. The handle 43 bears a parting-blade 44 which is preferably of some substance such as ivory with a wedge-shaped formation in cross-section. The inner end of the shaft 34 is provided with a universal joint 45 to which is connected an arm 46 bearing a roller 47 preferably, although not necessarily, 50 covered with a layer of corrugated rubber. The universal joint 45 permits the arm to be raised or lowered or turned sidewise at the will of the operator.

55 Mounted on the bearing 9 on the member 1 is an arm 48 supporting at its outer end

an apertured head 49 in which is mounted a fixed rod 50 provided with a plurality of apertures or recesses 51. Mounted in a pair of the recesses 51 are a pair of upright guides 52 for a purpose to be later described, one of which bears a supporting hook 53. In practice, the two guides 52 will be positioned on opposite sides of the central transverse line where the tools, to be later described, are arranged to engage the article 27, but by providing a plurality of apertures 51 the longitudinal position of the guides 52 may be varied to suit the requirements of the work to which the device is to be subjected. Secured on the member 30 on the rod 6 are a pair of upright supports 54 between which extends a rod 55 bearing adjustable collars 56. Rockably mounted on the rod 56 is the hub 57 of a knife-bearing arm 58, the inner end of which bears a circular cutting knife 59, positioned immediately below the center of the shaft 10 and the arm 58 is provided with an operating handle 60. The weight of the knife 59 is arranged to overbalance the arm 60 and normally hold the knife 59 in its lower or inoperative position. A pair of adjustable collars 61 are provided on the rod 6 for limiting the longitudinal movement of the tool-bearing-carriage.

55 The tool-bearing carriage is shifted on the ways 5 and 6 in one direction by means of a weight 62 to which is connected a flexible member 63 running over a pulley 64 and attached to a lug 65 on the carriage. The function of this counter weight is to normally shift the carriage to the left in Fig. 2, and this shifting movement is regulated through the medium of one of the fixed collars 61. In order to shift the tool-bearing carriage to the right in Fig. 2 there is provided on one of the cross-bars 31 a lug 66 to which is connected a flexible member 67 running over a pulley 68 mounted on a shaft 69 supported by a bracket 70 on the member 2. The flexible member also runs around a lower pulley 71 on a shaft 72 supported by brackets 73 to a pulley 74 suitably supported below the tool-bearing carriage. Positioned below the tool-bearing carriage 110 is a pedal 75 to the inner end of which is secured the flexible member 67.

115 In long experience in the manufacture of articles of this character in which the rolling up and formation of the bead by hand has heretofore been the customary practice, it has been found that no matter how carefully the bead is formed, unless pressed and the various spirally-wound layers of the wall of the article when rolled up to form a bead are adherent an opening or space occurs between the layers which do not adhere to each other and in which air is confined which expands during the subsequent curing of the rubber sufficiently to blow the bead apart or 120 125 130

break it or otherwise render it imperfect, so much so as to make the article commercially deficient and unmarketable. With this end in view, I provide a roller adapted 5 to run on the face of the bead after its formation for pressing the various spiral layers together, to iron out the wrinkles, to exclude air and air-bubbles, and to impart a perfect shape to the bead. The surface of 10 the roller is of any cross section desired and there is preferably placed on the arm 43 a rocking-lever 76 preferably fulcrumed at 77 and bearing on its inner end a roller 78 which can be forced downwardly into 15 engagement with the bead during the rotation of the article by raising the outer end of the lever 76 after the parting-knife 44 has performed its function and the lever 43 has been slightly raised to clear the article.

20 The operation of the device is as follows: The goods are usually made by dipping forms repeatedly in a bath until the required thickness is obtained for the article. It frequently happens that the upper or open 25 end of the dipped article is uneven and rough, and of course, is of the same thickness as the balance of the article. In order to smooth the upper end of the article and provide a strength-giving bead thereon, the 30 forms 26 on which the articles are made, are secured to the face plates 23 of the bushings 22. After the formation of the article has been accomplished the bushings 22 are successively slipped onto the shaft 18 and 35 locked there through the mechanism herein-before described, and this usually takes place with the shaft 10 running constantly. The tool-bearing carriage will, under ordinary circumstances, be to the left in its operative 40 position and the operator depresses the handle 60 of the arm 58 bearing the knife 59 causing the latter to engage the upper open neck of the article 27 to trim it, making a cut therein at a desired point. A release of 45 the handle 60 causes the knife 59 to fall by gravity out of engagement with the article. The operator then rocks the lever 43 downwardly so as to bring the parting blade 44 into the cut made by the knife and as the 50 armature shaft 34 is revolved it causes a vibratory motion of the blade 44 in the cut made by the knife during the revolution of the article 27 in unison with the rotation of the shaft 10. The function of the parting-blade 44 is to separate the severed edges of the 55 trimmed portion of the neck of the article and slightly raise the cut edges of the material of the neck from the form on which it has been made.

60 It will be pointed out that the lever 43 during the operation of the parting knife 44 to the article is held between the guides 52 comparatively loosely so as to permit the operator to use some discretion in the 65 manipulation thereof. If the operator de-

sire the lever 43 may be moved slightly longitudinal of the machine sufficient to cause the parting-blade 44 to roll up a bead on the article without the further application of any other tool, but this is not the usual procedure. On the contrary, after the parting-blade 44 has performed its function, the lever 43 is raised and the handle 46 bearing the roller 47 is swung down between the guides 52 to permit the rapidly-revolving roller 47 to engage the severed and upturned edge of the article, the result of which is that a bead on the article is rapidly rolled up by engagement with the roller 47. When the roller 47 is not in use, it is raised 80 upwardly and the handle 46 is supported out of the way in a convenient position in the supporting hook 53.

I claim:

1. The combination in a bead-forming machine embodying a rotatable article supporting member, of a trimming tool adapted to be brought into engagement with the open end of said article for trimming the latter, a vibratory carrying tool adapted to engage the article in the cut made by said trimming-tool for loosening the edges of said article from said form, and a bead-rolling mechanism for rolling up a bead on said article.

2. A bead-forming machine comprising a suitably-rotated article-carrying member, a longitudinally-shiftable carriage adjacent to said member, a shaft arranged transversely of the axis of rotation of said member, a combined parting and bead-forming tool, means for transmitting vibratory motion from said transverse shaft to said tool for rolling up a bead on said article.

3. A bead-forming machine comprising a suitably-rotated article-carrying member, a carriage mounted adjacent to said article-carrying member, said carriage being shiftable longitudinally with respect to said article, a trimming-tool carried by said carriage, and a combined vibratory parting and bead-rolling tool mounted on said carriage.

4. A bead-forming machine comprising a suitably-rotated article-carrying member, a carriage mounted adjacent to said article-carrying member, said carriage being shiftable longitudinally with respect to said article, a trimming-tool carried by said carriage, a combined vibratory parting and bead-rolling tool mounted on said carriage, and guiding means for said tool during its engagement with said article.

5. A bead-forming machine comprising a rotatable shaft, an article-carrying member on said shaft, a carriage shiftably mounted with respect to said shaft, a combined parting and bead-forming member mounted on said carriage, and means for imparting a vibratory movement to said forming-member during its application to the article.

6. A bead-forming machine embodying a rotatable holding member, and a non-revolute vibratory blade arranged for operation on the open end of the article during its rotation.

7. A bead-forming machine embodying a rotatable article-holding member, and a bead-forming tool applicable to the open end of said article during its rotation, and 10 means for vibrating said tool longitudinally of the axis of said article during its application thereto.

8. A bead-forming machine embodying an article holding member, and a non-revolute 15 bead-forming tool capable of rapid lateral

vibration during its application to the open end of said article.

9. A bead-forming machine embodying a rotatable article-holding member, and a non-revolute tool applicable to the open end 20 of said article during its rotation, said tool vibrating longitudinally of the axis of said article during its application thereto.

In testimony whereof I have hereunto set my hand in presence of two subscribing witnesses. 25

JOHN W. DENMEAD.
